UNITED STATES PATENT OFFICE

JOE J. ETTINGER, OF WARSAW, INDIANA, ASSIGNOR TO ZIMMER MANUFACTURING COMPANY, OF WARSAW, INDIANA, A CORPORATION

HOSPITAL BED

Application filed August 2, 1928, Serial No. 296,950.

The invention relates to hospital beds and it is particularly directed to a bed designed to accommodate a patient having a fractured leg or an illness where the patient 5 should not be moved.

It is a most difficult undertaking in a leg fracture case to remake the bed or to attend to the patient's calls of nature without danger of disturbing the injured leg.

10 The object of my invention is to provide a novel bed in which the foregoing disadvantages are overcome.

Other objects and advantages will be set out hereinafter.

15 The invention is illustrated in the accompanying drawings in which

Figure 1 is a perspective view of a bed embodying the invention; Fig. 2 a plan view of one of the clamps by which the adjustable rack is secured to the bed; Fig. 3 an elevational view, partly in section of one of the pivotal supports of the rack; Fig. 4 an elevational view of another of the pivotal supports; Fig. 5 a perspective view of the 25 detail of the supporting belts of the bed; Fig. 6 an elevational view of the belt securing and tightening device; Fig. 7 an end view of the said device; Fig. 8 a plan view of the bed and cot with the cross belts and 30 securing and tightening devices removed and Fig. 9 a fractional end view of the bed partly in section and partly broken away.

In the illustrative embodiment of the invention the bed is formed in the usual manner of the head 1, foot 2 and two attachable side rails 3 and 4. A suitable number of webs or bands 5 are provided, each of which has a loop 6^a secured to one end thereof. The loop-carrying end of each web or band 40 is passed outwardly over the rail 4 and then carried upwardly under the said rail. The opposite end of the web or band is then drawn through the loop and to the other rail 3. Each web or band is therefore looped 45 about the rail 4 at a selected point. The opposite end of each web or band is passed through aligned slots 5^a formed in the opposite sides of a roller 6 that is revolvably mounted in the bearings 7 secured to the rail 3. The pins 8 extend transversely

through the roller 6 at any desired angle relatively to each other, and as many pins may be provided as is desired. Each pin is headed at its opposite ends to prevent it from disengaging from the roller. Aper- 55 tures 9 are formed in the vertical flange of the rail 3 through which the pins 8 may be extended, when in line therewith, to lock the roller to the rail. The pins serve as levers to rotate the rollers for winding up the webs or bands and drawing them tight on the rails 3 and 4. The webs or bands support the patient temporarily when the cot 10 is lowered. 60

The cot 10 is of any convenient form and supports a suitable mattress with the usual bed under-coverings. 65

Rollers 11 and 12 are revolvably mounted respectively on the inner face of the end rails 13 and 14 of the bed and a suitable number 70 of straps 15, 16 is secured at one end to the rollers, the opposite ends of the straps being engageable upon the studs 17 which project from the opposite ends of the frame of the cot. 75

Suitable gears 18, 19 are secured to the shafts 20, 21 of the rollers 11 and 12, respectively, and mesh with the gears 22, 23 secured to the shaft 24 that is revolvably mounted in the bearings 25 formed on the 80 inner face of the side rail 4. A crank 26 is attachable or fixed to one end of the shaft 24 by which the latter shaft may be rotated to drive the rollers and wind up or unwind the straps 15, 16, to raise or lower the cot. 85 The cot is elevated until the top of the mattress or the coverings thereon firmly engage the webs or bands 5. The patient is now resting upon the mattress and is as comfortable as he would be on a regulation bed. 90

To change the coverings on the cot it is only necessary to lower the cot, detach the supporting straps 15, 16 therefrom and roll the cot from beneath the bed frame to gain full access to the cot. The patient remains 95 undisturbed on the webs or bands 5 and is supported thereby until the return of the cot. In attending to nature the cot will be lowered a sufficient distance and the proper web or band will be released from its roller 100

6 and permitted to rest upon the cot. A suitable vessel then may be deposited upon the cot at the proper point. The patient is supported upon the webs or bands until the released band is restored and the cot returned to its supporting position.

Any suitable form of mechanism for driving the rollers 11 and 12 will suffice. Should it be necessary to lock the rollers against rotation when the cot is in use suitable means for accomplishing such locking will be readily suggested, such as a pin 27 extended through aligned openings 28 in the roller and in the adjacent end rail of the bed.

In Figs. 1-4, the leg supporting and extension frame is illustrated, which consists of four posts or pipes 29 adapted to be attached to the bed posts by the clamps 30, the stem 30^a of each of which clamps extends through the bed post and is held in place by a nut on the stem. Nuts 31 on the arms 30^b, 30^c of the clamp hold the plate 32 firmly against the inner face of the bed post, the plate being loose on the said arms.

Jaws 33 are pivoted to the caps 34 that are threaded on the upper ends of the posts 29. The jaws support the rods or pipes 35 and 36 in longitudinally adjusted position, set screws 37 in the jaws securing the same to the rods or pipes. Upon the rods or pipes 35, 36, are adjustably mounted any number of jaws 38, each of which is pivoted to a similar jaw 39, a set screw 40 in jaw 38 being adapted to secure the jaw to the rod or pipe in any position thereon. The jaws 39 receive the rods or pipes 40, and similar double jaws 41 may be mounted on either or both rods or pipes 40 and adjustably support another rod or pipe 42. The rods or pipes 40 may be set at any angle relatively to the longitudinal axis of the bed so that the desired extension of the limb may be secured, the usual pulleys being mounted on the rods or pipes wherever desired, and the usual cords with weights thereon being passed over the pulleys and connected to the splint or to the leg, not shown. A wide range of adjustment of the extension device is thus possible and when once set they need not be disturbed in moving the cot for any purpose.

What I claim is:

1. A bed frame, a plurality of bands each engaged at one end to one side of the frame, a series of slotted and transversely apertured rollers mounted on the opposite side of the frame the slots of which are adapted to receive the opposite ends of the bands, members engaged in the apertures respectively by which to rotate the rollers for stretching the bands and apertures in the adjacent side of the frame adapted to receive the members to prevent unauthorized reverse rotation of the rollers respectively.

2. A bed frame, a plurality of bands each engaged at one end to one side member of

the frame, a series of transversely apertured rollers on the opposite side member of the frame and releasably engaging the other end of the bands respectively, the latter side member of the frame having apertures therein corresponding to the apertures in the rollers respectively and elongated pins slidably engaged in the apertures in the rollers respectively by which to rotate the rollers for stretching the bands, said pins being adapted to be moved into the apertures in the frame member for locking the rollers to said frame member.

Witness my hand and seal this 27th day of July, 1928.

JOE J. ETTINGER.
